HARLEY M. DUNLAP

UNITED STATES PATENT OFFICE.

HARLEY M. DUNLAP, OF BATTLE CREEK, MICHIGAN.

AIR-PUMP.

1,227,762.

Specification of Letters Patent.

Patented May 29, 1917.

Application filed October 17, 1916. Serial No. 126,130.

To all whom it may concern:

Be it known that I, HARLEY M. DUNLAP, a citizen of the United States, residing at Battle Creek, in the county of Calhoun and 5 State of Michigan, have invented certain new and useful Improvements in Air-Pumps, of which the following is a specification.

This invention relates to improvements in 10 air pumps.

The main object of this invention is to provide an improved double acting air pump which is of large capacity and requires but a relatively small amount of power for its 15 operation.

A further object is to provide an air pump having these advantages which is compact and simple in structure and at the same time not likely to get out of repair.

20 Further objects, and objects relating to details and economies of construction and operation will definitely appear from the detailed description to follow.

I accomplish the objects of my invention 25 by the devices and means described in the following specification. The invention is clearly defined and pointed out in the claims.

A structure constituting a preferred embodiment of my invention is illustrated in 30 the accompanying drawings forming a part of this specification, in which:

Figure I is a central vertical section of my improved pump, parts being shown in full lines.

35 Fig. II is an inverted view.

Fig. III is a detail perspective view of the rocker arm.

In the drawing, similar characters refer to similar parts throughout the several 40 views.

Referring to the drawing, I provide a base 1 having suitable supporting legs. Side by side on this base I mount a pair of low pressure cylinders 2, 2. These cylinders are 45 provided with heads 3 having seats 4 in their upper sides for the high pressure cylinders 5, the heads 3 constituting bases for such cylinders. The high pressure cylinders 5 are provided with heads 6. The cylinders

50 are in the form of tubes open at both ends and are clamped between their respective heads and bases, the cylinders 2 being secured by means of the bolts 7 carried by the base 1 and arranged through ears 8 on the heads 3 while the cylinders 5 are clamped

between the heads 3 and 6 by means of the bolts 9 carried by the heads 3.

High pressure cylinder delivery passages 10 are formed in the heads 6 and provided with valves 11. The passages 10 are connected by the pipe 12, one of the passages 10 being provided with a nipple 13 adapted to receive a hose. The high and low pressure pistons or plungers 14 and 15 are connected in pairs by the connecting rods 16 which are arranged through holes 17 in the heads 3.

The pistons are provided with packing rings 18 retained in place by the plates 19, the structure of the high and low pressure 70 pistons being substantially the same. These pistons or plungers are of the type which admits air above the piston on the down-stroke, the packings preventing its return on the up or work stroke.

75 A rocker arm, designated generally by the numeral 20, is provided with a journal 21 supported in bearings 22 mounted on the under side of the base and centrally between the cylinders. The arms 23 of the 80 rocker arm project upwardly and are bifurcated to receive the links 24 which are connected thereto by the pivots 25 and to the pistons 14 by the pivots 26. These pivots are disposed so that as the pistons approach 85 the end of their up stroke the pivots connecting the links to the piston and to the rocker arm approach a straight line relative to the axis of the rocker arm, the rocker arm swinging into the cylinders through the 90 openings 27 in the base, as clearly shown in Fig. I.

The openings in the heads 3 serve as ports between the high and low pressure pistons and these ports are controlled by the flexible 95 disk valves 28 which are arranged in the seats in the cylinder heads so as to be clamped by the high pressure cylinders, being retained thereby and also serving as gaskets for such cylinders. The valves have 100 ports 29 therein and fit the connecting rod 16 so as to serve as glands or gaskets therefor.

With this simple arrangement of parts I provide a structure which is of large capacity and may be easily operated, even under considerable pressures. The operating lever 30 is engaged in the socket 31 of the rocker arm journal 21 and this permits the operator to stand in an upright position to 110

operate the pump. As this lever or handle is oscillated the pistons are alternately operated, and the upstrokes, forcing the air from the low into the high pressure cylinders, discharge the air forced into the high pressure cylinders on the previous stroke. On the return stroke the air forced into the high pressure cylinder passes above its piston and a new charge of air is taken into the low pressure cylinders.

By arranging the operating mechanism as illustrated and described I secure an action somewhat like a toggle which provides for the greatest power toward the end of the stroke where the greatest power is required, the travel of the pistons being rapid at the beginning of the stroke and slower toward the end. This construction also results in a pump which develops a large amount of compression with a small amount of power. The structure is compact and may be easily mounted for operation on the running board of an automobile, the base being provided with feet 32 having perforations 33 adapted to receive screws or bolts when it is desired to permanently mount the pump, or these feet may be engaged by clamps, not illustrated, for temporarily mounting the base.

I have illustrated and described my improvements in an embodiment which I have found very practical. I have not attempted to illustrate or describe certain modifications which I contemplate or which might be desirable under certain conditions, as I believe the disclosure made will enable those skilled in the art to which my invention relates to embody or adapt the same as conditions may require or taste dictate.

Having thus described my invention, what I claim as new and desire to secure by Letters Patent, is:

1. In a structure of the class described, the combination of a base having openings therein, a pair of low pressure cylinders open at their lower ends seated on said base above its said openings, a pair of high pressure cylinders of substantially less diameter than said low pressure cylinders, heads for said low pressure cylinders having seats therein for said high pressure cylinders and constituting bases therefor, heads for said high pressure cylinders having delivery passages therein provided with valves, a coupling pipe connecting said delivery passages at the rear of their valves, one of said passages being provided with a delivery connection, bolts extending from said low pressure cylinder heads to said base and from said high pressure cylinder heads to said low pressure cylinder heads, pairs of high and low pressure cylinder pistons, connecting rods for said pairs of pistons disposed through said low pressure cylinder heads, disk valves for said high pressure cylinders disposed in said seats to surround

said connecting rod and constitute packing glands therefor and packing gaskets for said high pressure cylinder seats, a rocker arm pivotally mounted on said base centrally below said low pressure cylinders and having upwardly projecting arms which swing through said base openings into said cylinders as the rocker arm is oscillated, and links connecting said arms to said low pressure pistons, the pivots connecting said links to said arms being so disposed relative to the axis of the rocker arm that they approach a straight line as the pistons near the ends of their work stroke.

2. In a structure of the class described, the combination of a base having openings thereon, a pair of low pressure cylinders open at their lower ends seated on said base above its said openings, a pair of high pressure cylinders of substantially less diameter than said low pressure cylinders, heads for said low pressure cylinders having seats therein for said high pressure cylinders and constituting bases therefor, heads for said high pressure cylinders having delivery passages therein provided with valves, a coupling pipe connecting said delivery passages at the rear of their valves, one of said passages being provided with a delivery connection, bolts extending from said low pressure cylinder heads to said base and from said high pressure cylinder heads to said low pressure cylinder heads, pairs of high and low pressure cylinder pistons, connecting rods for said pairs of pistons disposed through said low pressure cylinder heads, disk valves for said high pressure cylinders disposed in said seats to surround said connecting rod and constitute packing glands therefor and packing gaskets for said high pressure cylinder seats, a rocker arm pivotally mounted on said base, and links connecting said arms to said low pressure pistons.

3. In a structure of the class described, the combination of a base, a pair of low pressure cylinders open at their lower ends mounted on said base, a pair of high pressure cylinders of substantially less diameter than said low pressure cylinders, heads for said low pressure cylinders having seats therein for said high pressure cylinders and constituting bases therefor, heads for said high pressure cylinder having delivery connections, pairs of high and low pressure cylinder pistons, connecting rods for said pairs of pistons disposed through said low pressure cylinder heads, disk valves for said high pressure cylinders disposed in said seats to surround said connecting rod and constitute packing glands therefor and packing gaskets for said high pressure cylinder seats, a rocker arm pivotally mounted on said base, and links connecting said arms to said low pressure pistons, the pivots con-

necting said links to said pistons and to said arms being so disposed relative to the axis of the rocker arm that they approach a straight line as the pistons near the ends of 5 their work stroke.

4. In a structure of the class described, the combination of a base, a pair of low pressure cylinders open at their lower ends mounted on said base, a pair of high pressure cylinders of substantially less diameter than said low pressure cylinders, heads for said low pressure cylinders having seats therein for said high pressure cylinders and constituting bases therefor, heads for 10 said high pressure cylinders having delivery connections, pairs of high and low pressure cylinder pistons, connecting rods for said pairs of pistons disposed through said low pressure cylinder heads, valves for said 15 high pressure cylinders disposed in said seats, a rocker arm pivotally mounted on said base, and links connecting said arms to said low pressure pistons, the pivots connecting said links to said pistons and to said 20 arms being so disposed relative to the axis of the rocker arm that they approach a straight line as the pistons near the ends of 25 their work stroke.
5. In a structure of the class described, the combination of a base, a pair of low pressure cylinders open at their lower ends mounted on said base, a pair of high pressure cylinders of substantially less diameter than said low pressure cylinders, heads for 30 said low pressure cylinders having seats therein for said high pressure cylinders and constituting bases therefor, heads for said high pressure cylinders having delivery connections, pairs of high and low pressure 35 cylinder pistons, connecting rods for said pairs of pistons disposed through said low pressure cylinder heads, disk valves for said high pressure cylinders disposed in said seats to surround said connecting rod and 40 constitute packing glands therefor and packing gaskets for said high pressure cylinder seats, a rocker arm pivotally mounted on said base, and links connecting said arms to said low pressure pistons. 45
6. In a structure of the class described, the combination of a base, a pair of low pressure cylinders open at their lower ends mounted on said base, a pair of high pressure cylinders of substantially less diameter than said low pressure cylinders, heads for 50 said low pressure cylinders and constituting

bases for said high pressure cylinders, heads for said high pressure cylinders having delivery connections, pairs of high and low pressure cylinder pistons, connecting rods 60 for said pairs of pistons disposed through said low pressure cylinder heads, valves for said high pressure cylinders disposed in said seats, a rocker arm pivotally mounted on said base, and links connecting said arms 65 to said low pressure pistons.

7. In a structure of the class described, the combination of a base, a pair of low pressure cylinders mounted thereon side by side, a pair of high pressure cylinders 70 mounted on said low pressure cylinders in axial alinement therewith, connected pistons for said high and low pressure cylinders, means for delivering air from said low pressure cylinders to said high pressure 75 cylinders, delivery connections for said high pressure cylinders, a rocker arm pivotally mounted on said base centrally between said low pressure cylinders, and links connecting the ends of said rocker arms with 80 the under sides of the low pressure cylinder piston centrally thereof and disposed so that the point of pivotal connection of a link with the rocker arm, and the pivotal point of the rocker arm approach a straight 85 line as the piston nears the upper end of its stroke.

8. In a structure of the class described, the combination of a base, a pair of low pressure cylinders mounted thereon side by side, 90 a pair of high pressure cylinders mounted on said low pressure cylinders in axial alinement therewith, connected pistons for said high and low pressure cylinders, a rocker arm pivotally mounted on said base centrally below said low pressure cylinders, the arms of the rocker arm being adapted to swing into the low pressure cylinders on the compression strokes, links connecting the ends of said rocker arm to the low pressure 95 pistons, means for admitting the compressed air from the low pressure cylinders to the high pressure cylinders, and an outlet connection for the high pressure cylinders. 100

In witness whereof, I have hereunto set my hand and seal in the presence of two witnesses.
